A. GREENSTEIN
ADJUSTABLE HEADGEAR

Filed May 2, 1928

INVENTOR.
ABRAHAM GREENSTEIN.
BY *M. Theodore Simmons*
ATTORNEY

UNITED STATES PATENT OFFICE.

ABRAHAM GREENSTEIN, OF BROOKLYN, NEW YORK.

ADJUSTABLE HEADGEAR.

Application filed May 2, 1928. Serial No. 274 450.

My invention relates to means for adjusting the size of head gear.

Such an arrangement permits the making up of a few standard sizes of head gear and to accommodate the same to the different sized heads by an adjustable strap or belt arrangement. This is obviously more economical than making up a large variety of sizes of head gear.

19 It is one object of my invention to provide an improved and readily operable method of adjusting the size of the head gear.

It is a further object of my invention to secure the strap in a cheap but firm manner 15 in position in the head engaging portion of the head gear.

It is a further object of my invention to arrange the adjusting means within the cap so that no portion thereof is exposed to contact with the head of the wearer.

My invention may be best understood from the drawings, wherein,

Figure 1 is a bottom plan view of a cap to which my invention is applied;

25 Fig. 2 is a cross section on the line II—II of Fig. 1;

Fig. 3 is a modified form of eyelet engaging means, and

Fig. 4 is a plan view with parts being 30 broken away and parts being in section to facilitate illustration of my invention as applied to a hat.

Referring to Fig. 1, the cap comprises a body portion 11, a head engaging portion 12, a visor 13, and a sweat band 14. The cap is provided with a lining 16 that is slotted as indicated at 17, beneath the sweat band 14.

Referring to Fig. 2, the head engaging portion 12 is turned inwardly to form a hem, 40 within which is a stiffening band 18. A strap 19 is provided with a casing 20 that is secured to the hem and stiffening band 18, thus maintaining the strap 19 in place in the head engaging portion of the cap. The casing 20 encloses the strap 19 throughout the major portion thereof, but the ends of the strap project beyond the casing 20 and 45 through the slits 17 as shown best in Fig. 1. There the strap is provided with a plurality of eyelets 21 and an eyelet engaging means 22 which in the form shown in Fig. 1 is an ordinary buckle. Thus, by varying the position

of the hook of the buckle 22 with respect to the eyelets, the size of the head portion of the cap is varied.

55 In Fig. 3 the strap 19 is shown as provided with the eyelets 21 and a hook shaped member 23 for engaging the eyelets, the member 23 being secured in a loop 24 of the strap.

In Fig. 5 I have shown my invention as applied to a hat. The hat has a crown portion 31 and a head engaging portion 32 with a brim 33. The strap 34 is maintained adjacent the head engaging portion 32 by forming a pocket 35 in the lining 36. The pocket 35 is 60 formed by turning the end 37 of the lining 36 inwardly so as to surround the strap, and then stitching the lining to the crown of the hat in a size to just accommodate the strap 34, the stitching being so located as to maintain 65 the strap always adjacent the head engaging portion. The sweat band 38 may be provided to protect the head of the wearer from the adjusting buckle 39 of the strap 34, as described above for the cap shown in Fig. 1. 70

75 Modifications may be made in the arrangement and location of parts within the spirit and scope of my invention and such modifications are intended to be covered by the appended claims.

I claim:

1. In a head gear, a body portion, a head engaging portion, a lining, a strap, a casing enclosing said strap, said casing being secured in said head engaging portion within said lining, slits in said lining, the free ends of said strap projecting beyond said casing and through the slits in said lining, and having means for adjustably securing the strap ends together.

85 2. In a headgear, a body portion, a head engaging portion, a lining, a sweatband within the head engaging portion, a strap, a casing enclosing the strap, said casing being secured in said head engaging portion within said lining, slits in said lining beneath said sweatband, the free ends of said strap projecting beyond said casing and through the slits in the lining and having means for adjustably securing the strap ends together, said means 95 also being located beneath said sweatband when in adjusted position.

100 In testimony whereof I affix my signature.
ABRAHAM GREENSTEIN.
